UNITED STATES PATENT OFFICE.

PAUL D. MATVEOFF, OF WORCESTER, MASSACHUSETTS.

MECHANICAL TOY.

Application filed December 6, 1924. Serial No. 754,435.

The principal object of this invention is to provide a construction in which rotating rests located at a distance apart can be caused to co-operate in such a manner that 5 an image mounted on one of them can be made to jump automatically and land in the other and the rotation of both will continue.

The invention involves various features of construction and combinations of parts to 10 provide for manufacture in a simple and inexpensive way as will appear hereinafter.

Reference is to be had to the accompanying drawings, in which—

Fig. 1 is a plan of a toy constructed in accordance with this invention;

Fig. 2 is a side view;

Fig. 3 is a similar side view showing the position of the parts when the jump is made from one rest to another;

Fig. 4 is an outside end view of the operating end of the machine;

Fig. 5 is a sectional view on the line 5—5 of Fig. 2;

Fig. 6 is a diametrical sectional view of 25 the controlling wheel;

Fig. 7 is a sectional view on the line 7—7 of Fig. 2 showing a part of the mechanism at the other end;

Fig. 8 is a diametrical sectional view of 30 the wheel at that end;

Fig. 9 is a sectional view on the line 9—9 of Fig. 2 showing an additional feature;

Fig. 10 is an inside view of the barrier with the cover or disc removed;

Fig. 11 is a side view of the inner side of 35 the cover or disc; and

Fig. 12 is a plan view of this part of the device with one side broken away to show the bottom.

The toy is constructed with a frame 10 which may conveniently be made of sheet metal and is provided with legs 11 at opposite ends and preferably with a standard 12 at the center holding a barrier 13 which 40 extends across the device. The idea is to cause an image 37 to leap from a rest 36 over the barrier to another rest as shown in Fig. 3.

Extending between two sheet metal walls 14 and 15 at opposite ends of the frame and 50 constituting a part thereof is a shaft 16. On one end this shaft is provided with a sheet metal gear 17 fixed to it. This gear is formed of sheet metal pressed outwardly at the center to leave a circular portion in 55 a plane beyond the plane of the rest of the wheel. This circular portion can be provided with gear teeth in any desired way arranged in a plurality of sets, in this case two. I have shown these two sets of gear 60 teeth formed by cutting through the sheet metal on three sides of each tooth 23. The metal is bent at right angles back into another plane having the teeth projecting, located diametrically opposite each other and 65 concentric. I have two sets of longer teeth 18 formed by longer perforations and there are two series of projections 23 arranged in two opposite semi-circles and extending out a short distance, but not as far as the teeth 70 formed between the perforations 18 and constituting the remainder of the gear. The purpose of this construction is to permit a pinion 20 to mesh with the teeth 23. The pinion 20 preferably is of sheet metal, 75 mounted on a cross shaft 21 which is the driving shaft and is provided with a crank handle 22 for operating it. This shaft is rotated by the operator and it carries the pinion around with it.

It will be noted that this wheel 17 has a flange or face offset backwardly from the gear proper and of circular form. This is provided with two cams 25 on the outer edge, the two cams being in the same cylindrical surface but having cam surfaces for engaging a trigger 26 pivoted on the shaft 21 and provided with a spring 24 for forcing it forward quickly. It rides up in turn on the respective cam surfaces, as shown 80 in Fig. 2, and then suddenly snaps off the abrupt end thereof at 27 so that the trigger is projected suddenly forward. This is the driving element for causing the jumping action referred to above.

It is to be noted that the shaft 16 passes

through a block 29 and that the shaft 21 has its bearing in that block. Also mounted to rest in the block is a vertical shaft 30. This shaft has a pinion 31 on it projecting out far enough to engage in the gear slots 18 and located high enough so that it does not touch the gear teeth 23. Therefore during most of the rotation of the shaft 16 this pinion 31 will remain stationary. The shaft on which it is mounted is provided with a spring 32 surrounding it and pressing it down so that a pin 33 at the bottom is forced into a slot 34 perpendicular to the shaft 16. This holds in transverse position the frame 35 which is fixed to the top of the shaft in a fixed definite position. This frame 35 is in the form of two diametrically opposite arms which support inclined rests 36 for the images 37 which are to be operated. Each one of these rests has a slot 38 in the rear for the reception of the trigger 26. It will be obvious that the operation of the trigger in that slot, when one of the images is in place, is to engage the rear end of a flat plate 39 on the bottom of the image and force the same forwardly. The object is for it to jump from the position shown in full lines to the position shown in dotted lines in Fig. 3.

It will be seen that as far as this part of the device is concerned, the wheel 17 will rotate continuously as long as the crank is turned and that the frame 35 will rotate intermittently. This intermittent motion carries the frame through a semi-circle and always brings it to rest in the transverse position shown in Fig. 1, after its operation is stopped. It will be noted that each of the rests has at the rear end two inwardly extending flanges 40 extending up from its floor to prevent the images sliding out backwardly. At the front each rest is provided with a pair of separated inwardly extending flanges 41 spaced from the bottom to allow the flat base plate 39 to be forced out by the trigger.

On the other end of the machine fixed to the shaft 16 there is a metallic wheel 42. This is made like the wheel 17 or at least similar to it, but it does not have to have anything corresponding with the gear teeth 23. In place of those there is a blank space 44 extending circularly around concentric to the center and four perforations 18 arranged in two opposite sets as described before. The parts at this end are similar to the parts at the other end and need not be described in detail. They are given the same relative numbers and perform the same functions. The trigger 26 is employed and the wheel 42 is provided with the cams 25 for operating it but these cams are located in this instance on the other side of this wheel.

Fixed on the shaft 16 are a gear 50 and a circular disc 51. A short shaft 52 is mount-

ed in a bearing on the barrier 13 and has a pinion 53 meshing with the gear 50. This pinion has an eccentric stud 54 which, during its rotation, works back and forth in a longitudinal slot 55 in a lever 56 pivoted freely on the shaft 16. The pinion 53 is located directly under the shaft 16. On its upper end the lever 56 has a projection or shelf 57. The lever oscillates as the shaft 16 turns and the shelf 57 swings back and forth alternately under two openings 58 in a sheet metal frame 59 over the disc 51. Marbles 60 are placed in this frame and as the shelf swings and exposes the openings the marbles will roll down along tracks 61 to the bottom, first on one side and then on the other.

In the operation of the rest of the device the operator turns the crank 22, thus rotating the shaft 16 through the continuous gear 18-23. The shaft therefore rotates continuously and operates the marble releasing device. When the four teeth or perforations 18 come to the top they will engage the pinion 31 and rotate it a half revolution and then lose their control over it and pass on beyond it. This rotates the frame 35 through a half revolution and brings it to stop in the position shown in the various figures with the pin 33 in the shallow slot 34. Just as it comes to stop the trigger 26 drops off the abrupt surface 27 and gives the plate 39 a blow which sends the image 37 across where it will land in the rest 36 directly opposite. It will be noted that these rests are all arranged at the same inclination so that the jump will be upward and the landing place will be at the proper inclination to receive the dropping image. The forward ends of the rests are provided with flanges 41 which prevent the image from sliding out of the rest and cause it to settle back inside it. The image strikes over the wall 40 and would go farther if it were not for this construction. All this happens while the two frames 35 are at rest but while the shaft 16 is rotating. When the rests are rotated another half revolution and the rest which has just received the image in Fig. 3 is turned around to the opposite position at that end of the figure, the image is ready to be driven over to the power end of the machine by the second trigger. The parts are so timed and the images so weighted that with an ordinary speed of rotation the images will just land in the desired places. Of course it will be obvious that two images can be used at once, one jumping in each direction and that they both jump when the rests are stationary. Any kind of images can be used but race horses are shown.

I am aware of the fact that modifications can be made in the details of construction without departing from the scope of the in-

vention as expressed in the claims. Therefore I do not wish to be limited to all the details of construction herein shown and described, but what I do claim is:—

- 5 1. In a toy, the combination with a rotatable rest, means for rotating the rest throughout a complete circle, of an image adapted to rest thereon, means operated by the first named means for automatically engaging the image when the rest comes to a predetermined point in the path of rotation and forcing the image out of the rest to cause it to be projected therefrom, and another rest located in position to receive the 15 image projected from the first rest.

2. In a toy, the combination with a pair of rotary rests, both rests being located at parallel inclinations, one in front of the other, of a trigger located at the rear of 20 one rest, means for operating the trigger to engage an image thereon and propel it up the incline of that rest and through the air, means for then turning both rests around half way so that the rest which has just received the image will be behind the other rest and in alignment with it, and means for automatically engaging the image on the second rest and projecting it forward through the air, each rest being in position 25 when at rest to receive the image propelled through the air from the other rest.

3. In a toy, the combination of a pair of upwardly inclined rests located at a distance apart, movable to a position in alignment 30 with each other, an image resting freely on one of the rests, and means for automatically projecting said image from it and propelling it through the air, the other rest being located in a position at that time to receive the image, each rest having inwardly and upwardly extending flanges at the lower rear end to prevent the image from sliding out of the same and being provided with similar flanges on the front end but spaced 35 from the floor of the rest to permit the image to be discharged forwardly.

4. In a mechanical toy, the combination of two pairs of rests, each pair consisting of two oppositely inclined rests mounted at opposite ends of the toy and arranged on opposite sides of the toy and having a rotary frame connecting them, means for rotating each frame through a half revolution and then stopping it in definite position 50 with a rest of one pair in alignment with one of the other rests, and means for projecting an image from the rest of one pair through the air toward a rest of the other pair.

5. In a toy, the combination with an operating shaft, of a wheel operated thereby continuously when the shaft is turning, a second shaft, means connected with said wheel for intermittently operating the second shaft, and a frame carried by the sec- 65

ond shaft and having a pair of oppositely disposed rests thereon, the turning means for the second shaft being arranged to turn it half way around every time it operates.

6. In a mechanical toy, the combination with a driving shaft, of a main shaft, means whereby the main shaft is driven with the driving shaft at all times, means whereby the third shaft will be rotated intermittently from the main shaft throughout a half revolution every time it is rotated, means for stopping the third shaft when it has completed exactly a half revolution and holding it there in such a way that it can be started to rotate again, a frame on the third shaft, 70 and a pair of rests on the opposite ends of the frame for a jumping image or the like.

7. In a mechanical toy, the combination with a driving shaft and a pinion thereon, of a main shaft, a gear on the main shaft meshing with the pinion so that the main shaft is driven with the driving shaft at all times, said gear having certain groups of teeth projecting beyond the ends of the main teeth of the gear, a third shaft having 75 a pinion thereon located in such position as to mesh with the projecting teeth but not with the main teeth of said gear, whereby the third shaft will be rotated intermittently, the relation between the number of teeth on the pinion on the third shaft and the number of projecting teeth in each group being such that the third shaft will be driven throughout a half revolution every time it is rotated, means for stopping the third 80 shaft when it has completed exactly a half revolution and holding it there in such a way that it can be started to rotate again by the positive engagement of the gear teeth with the pinion, a frame on the third shaft, 85 and a pair of rests on the opposite ends of the frame for a jumping image or the like.

8. In a mechanical toy, the combination with a driving shaft and a pinion thereon, of a main shaft, a gear on the main shaft meshing with the pinion so that the main shaft is driven with the driving shaft at all times, said gear having certain groups of teeth projecting beyond the ends of the main teeth of the gear, a third shaft having 100 a pinion thereon located in such position as to mesh with the projecting teeth but not with the main teeth of said gear, whereby the third shaft will be rotated intermittently, the relation between the number of teeth on the pinion on the third shaft and the number of projecting teeth in each group being such that the third shaft will be driven throughout a half revolution every time it is rotated, means for stopping the third 105 shaft when it has completed exactly a half revolution and holding it there in such a way that it can be started to rotate again by the positive engagement of the gear teeth with the pinion, a frame on the third shaft, 110 and a pair of rests on the opposite ends of the frame for a jumping image or the like.

9. In a mechanical toy, the combination with a driving shaft having a pinion thereon, of a main shaft having a gear with 115 120 125

130

- which the pinion constantly meshes, said gear having two opposite series of teeth projecting beyond its main teeth, a third shaft having a pinion in position to mesh with the projecting teeth only and having a frame thereon provided with a pair of rests for carrying images or the like, a trigger having a spring for forcing it forward to engage an image carried by one of the rests and cause it to be projected therefrom, and means on the main shaft for controlling the trigger so that the trigger will act when one of the rests has been brought around to a predetermined position.
10. In a mechanical toy, the combination with a driving shaft having a pinion thereon, of a main shaft having a gear with which the pinion constantly meshes, said gear having two opposite series of teeth projecting beyond its main teeth, a third shaft having a pinion in position to mesh with the projecting teeth only and having a frame thereon provided with a pair of oppositely inclined rests to be operated, a wheel on the main shaft having a pair of cams, a trigger freely pivoted on the driving shaft and having a spring for forcing it forward to engage an image carried by one of the rests and cause it to be projected therefrom, the cam constituting means for controlling the trigger and the projections on the cam being so located with respect to the said projecting gear teeth that the trigger will act when one of the rests has been brought around to a predetermined position.
11. In a mechanical toy, the combination with a main shaft, a gear thereon having two opposite series of teeth, a driven shaft having a pinion in position to mesh with the teeth only and having a frame thereon provided with a pair of oppositely inclined rests to be operated, a wheel on the main shaft having a pair of cams, a trigger having a spring for forcing it forward to engage an image carried by one of the rests and cause it to be projected therefrom, the cam constituting means for controlling the trigger and the projections on the cam being so located with respect to the said gear teeth that the trigger will act when one of the rests has been brought around to a predetermined position.
12. In a mechanical toy, the combination of a driving shaft, a main shaft extending along the machine and driven constantly by the driving shaft, a pair of triggers one near each end of the main shaft, means at the ends of the main shaft for operating the triggers periodically, a frame at each end having rests thereon for a toy or image, means operated by the main shaft for rotating said frames half way around and then bringing them to rest with the rests parallel to the main shaft, said operating means for the triggers being so arranged with respect to the main shaft that the triggers will operate when the rests come to positions substantially parallel with the main shaft.
13. In a mechanical toy, the combination of a driving shaft, a main shaft extending along the machine and driven constantly by the driving shaft, a cam wheel at each end of the main shaft, a pair of triggers one controlled by each of the cam wheels and adapted to be operated thereby periodically, a pair of frames, one at each end, having inclined rests thereon for a toy or image, means operated by the main shaft for rotating said frames half way around and then bringing them to rest with the rests parallel to the sides of the machine, each cam wheel being so arranged with respect to the main shaft that the triggers will operate when the rests come to the sides of the machine.
14. In a mechanical toy, the combination of a driving shaft and a main shaft, a pinion on the driving shaft for driving the main shaft, a wheel on the main shaft consisting of sheet metal provided with perforations extending all the way around the center and meshing with said pinion and having groups of teeth extending farther beyond the center to provide means for actuating another element intermittently, said wheel having an integral flange thereon provided with a plurality of cam surfaces, and a trigger mounted on the driving shaft and adapted to be operated by said cam surfaces for the purpose described.
15. In a mechanical toy, the combination of a driving pinion, a wheel consisting of sheet metal provided with spaced perforations extending all the way around the center and meshing with said pinion and having groups of teeth extending farther beyond the center to provide means for actuating another element intermittently.
16. In a mechanical toy, the combination of a main shaft adapted to be operated constantly, a pair of rests rotatably mounted at each end of the main shaft, means connected with the main shaft for intermittently rotating said rests at each end, means connected with the main shaft for periodically forcing an image carried by one of the rests through the air toward one of the other rests, and a transverse barrier between the ends of the main shaft in such position that said images are adapted to pass over it in their flight through the air.
17. In a toy, the combination of a pair of rests, means for intermittently moving said rests and bringing them to a stop simultaneously in positions in alignment with each other, an image resting freely on one of the rests, and means operatively connected with the first-named means to operate in a definite relation thereto for automatically projecting said image therefrom and propelling it through the air toward the other rest, said

other rest being located at that time by the first-named means in position to receive the image thereon.

18. In a toy, the combination with a rotatable rest and means for rotating the rest, of an image adapted to rest on said rest, means for automatically engaging the image

and projecting it from the rest, and means operated by the first-named means for actuating said projecting means.

In testimony whereof I have hereunto affixed my signature.

PAUL D. MATVEOFF.
